UNITED STATES PATENT OFFICE.

JOHNSON S. WAUGH, OF PROSPECT, OHIO, ASSIGNOR OF ONE-HALF TO
K. E. RANDALL AND L. GAST, OF SAME PLACE.

CAR-COUPING.

SPECIFICATION forming part of Letters Patent No. 288,527, dated November 13, 1883.

Application filed June 23, 1883. (No model.)

To all whom it may concern:

Be it known that I, JOHNSON S. WAUGH, of Prospect, in the county of Marion and State of Ohio, have invented a new and useful Improvement in Car-Couplings; and I do hereby declare that the following is a full, clear, and exact description of the same.

My invention is an improved coupling for railway-cars. The object of it is to effect the coupling of the cars without requiring the attendant to stand between, either for the manipulation of the pin or link.

In the accompanying drawings, Figure 1 is an end elevation of the car with the coupling attached. Fig. 2 is a side elevation of the coupling as applied to the car. Fig. 3 is a plan view.

In the drawings, A represents an ordinary bunter or draw-head. Below it is hinged a guide-plate, B. It is made with a curved end, *a*, as shown in Fig. 2, which curved end preferably has side flanges, *1 1*, to guide the link to the opening in the draw-head. The rear part of the plate is preferably cut away or formed so as to leave two arms, *b b*, which are hinged upon a rod, *c*, in two vertical arms, C. These arms extend down from the rear bar, *d*, of an iron frame, D, the bar *d* being bolted to the front of the car-frame. The iron frame D is composed of a front bar, *e*, two cross-pieces, *ff*, at the ends, and two interior slotted cross-pieces, *g g*, all extending from the front to the rear bar. Through the slots in the bars *g g* are passed arms *h h*, fixed to a pin-carrier, H. The lower ends of the arms *h* are pivoted to the arms of the guide-plate by a rod, *i*. On the upper side of the pin-carrier, at each end, is an ear, *k*, in which is inserted the inner end of a lever, K. These levers (there being one on each side preferably) are pivoted in the upper ends of standards *l* on the cross-piece *f*. The outer ends of the levers extend outside of the car, or far enough to be within easy reach of the operator without requiring him to go between the cars. The parts are so adjusted that when the pin-carrier is down upon the cross-bars *g* the guide-plate for the link hangs directly

down underneath the draw-head, and by depression of either one of the levers the guide 50 can be raised.

In order to provide for raising the guide when the operator is upon the platform of the car, I have provided a bell-crank lever, L. This is attached to the inner ends of the levers 55 K, or to any suitable part of the pin-carrier, so that the operator may raise the carrier and the guide by pulling back the upper end of the bell-crank lever. This lever is pivoted upon the upper end of a standard, *n*, set in 60 the cross-bar *d*. The pin-carrier is formed with a hole or slot, *2*, so that the pin can be passed down and hung by its head in the slot. When, therefore, the pin-carrier is raised, it lifts the pin from the cavity of the 65 draw-head and allows the link to enter. At the same time the guide lifts the link and directs it into the draw-head, and at that moment the operator releases the lever, which allows the guide and pin-holder to drop, 70 dropping also the pin into its hole and connecting the link.

The apparatus as constructed is complete, and may be applied to any ordinary draw-head and car by simply bolting the cross-bar *d* to the end of the car, as heretofore described. 75

The form and construction of the frame may be changed without departing from the spirit of my invention, the essential feature of which 80 is the guide and pin-holder.

Having thus described my invention, what I claim as new, and desire to secure by Letters Patent, is—

1. The combination, with a draw-head, of 85 standards *n*, a pivoted lever, L, swinging pin-carrier suspended from said lever, and a pivoted guide below the draw-head, connected to the said pin-carrier.

2. The combination, with a draw-head, of 90 a pivoted lever, L, a pivoted guard, B, and an intermediate pin-carrier connected both to the pivoted lever and to the said guard, and adapted to operate substantially as described.

3. The frame adapted to be bolted to the 95

front end of the car, and having slotted cross-pieces *g g*, the pin-carrier having arms passing through the slotted pieces *g g*, the pivoted guide connected to said arms, and the 5 levers connected to the pin-carrier, all as set forth.

4. In a car-coupling, the pin-carrier having a slot to receive and hold the pin, in combination with the lever *L* and connecting-rod.

In testimony whereof I have signed my name to this specification in the presence of two subscribing witnesses.

J. S. WAUGH.
